Inventor,

James P. Freeman.

UNITED STATES PATENT OFFICE.

JAMES P. FREEMAN, OF CHICAGO, ILLINOIS, ASSIGNOR TO THE HOME
TELEPHONE COMPANY, OF ILLINOIS.

ELECTRIC TELEPHONE.

SPECIFICATION forming part of Letters Patent No. 257,686, dated May 9, 1882.

Application filed July 21, 1881. (No model.)

To all whom it may concern:

Be it known that I, JAMES P. FREEMAN, a citizen of the United States, residing at Chicago, in the county of Cook and State of Illinois, have invented certain new and useful Improvements in Electric Telephones; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to electric telephones adapted to the transmission of articulate speech by means of electrical waves or impulses traversing a circuit.

The object of my improvement is to obtain a greater permanency of adjustment of the electrodes.

To this end it consists mainly in holding the electrode operated by the diaphragm in contact therewith by magnetic force, said electrode being attached to the keeper of a permanent magnet with which the keeper is in contact along one edge or line only, so that the keeper can oscillate on the magnet in unison with the vibrations of the diaphragm.

In order that my invention may be clearly understood, I have illustrated in the annexed drawings and will proceed to describe one form thereof which I have practically tested and found very effective.

Figure 1 is a front elevation of the door or side of a box to which my invention is shown as connected. Fig. 2 is a rear elevation of the same. Fig. 3 is an edge view. Fig. 4 is a transverse section on line $x-x$ of Fig. 2. Fig. 5 is a separate view of the permanent magnet and its keeper provided with the electrode to be operated by the diaphragm.

The same letters of reference indicate like parts in all the figures.

The door or side A, preferably made of hard rubber, is provided with the usual central flaring depression and orifice, covered on the inside by the diaphragm B, which may be encircled around its periphery by a C-ring of soft rubber, and held in place by a number of

clamping spring-fingers, b b, bearing on the 50 rubber ring.

The electrode E, which may be a pin of platinum, is secured to the soft-iron keeper D of the permanent magnet C, which is in this instance an ordinary horseshoe-magnet. The 55 magnet is arranged to reach to about the central line of diaphragm with its poles, it being at its neutral end secured to the door A by a clamp-bar, c, and a screw, c'. A thin piece, c², is placed between the door and the magnet to 60 separate it the proper distance from the diaphragm. The keeper is preferably made flat, as shown, and the end of the electrode E extending to and touching the center of the diaphragm is of such a length that it holds that 65 portion of the keeper to which it is attached separated from the magnet, and only permits the extreme edge of the keeper to remain in contact with the magnet, as clearly shown in Fig. 4. Thus the electrode E is held in contact with the diaphragm by the attraction of the magnet C exerted on the keeper D, which can oscillate on the magnet in unison with the vibrations of the diaphragm. The force with which the electrode E is pressed against the 70 diaphragm may be primarily regulated by proper adjustment of the magnet and keeper to make the instrument more or less sensitive. When once adjusted no subsequent adjustments will be required. In order that the 75 keeper may not slip on the magnet, I provide the latter with shoulders c³ c³, against which that edge of the keeper in contact with the magnet abuts.

The fixed electrode—the carbon button H— 80 is carried in a cup, F', of a bridge or cross-bar, F, the ends of which rest on elastic cushions composed of rubber blocks I, and are secured by screw J passing through the rubber blocks into taps or nuts in the door A. In securing 85 the cross-bar by the screws the rubber blocks are compressed, so that they will force the cross-bar back on loosening the screws. The cross-bar can thus be readily adjusted to bring the carbon button H into proper position with respect to the electrode E.

One pole of the battery is connected by wire L to the cross-bar F, while the other pole there-

of is preferably connected by the wire K to the diaphragm, though it may be connected by a wire, M, to the magnet C instead.

I do not claim broadly the application of a permanent magnet for supporting by its keeper one electrode of a telephonic transmitter; but I believe myself to be the first who so combined these parts that the electrode is held in contact with the diaphragm solely by the magnetic attraction exerted on the keeper by the magnet.

Having thus described my invention, what I claim is—

1. The combination, substantially as before set forth, of the diaphragm, the fixed permanent magnet, the flat oscillatory keeper in constant contact with said magnet, and the electrode carried by the keeper and held in contact with the diaphragm solely by magnetic attraction exerted on the flat side of the keeper.
2. The combination, substantially as before set forth, of the diaphragm, the fixed permanent

magnet, the flat oscillatory keeper in constant contact with said magnet, the electrode carried by the keeper and held in contact with the diaphragm solely by magnetic attraction exerted on the flat side of the keeper, and the fixed electrode.

3. The combination, substantially as before set forth, of the diaphragm, the electrode operated thereby, and the oscillatory keeper, of a permanent magnet carrying said electrode, the fixed electrode, the cross-bar supporting said fixed electrode, and the elastic cushions interposed between the cross-bar and the door or side to which the cross-bar is secured by screws.

In testimony whereof I affix my signature in presence of two witnesses.

JAMES P. FREEMAN.
